(21) Appl. No.: **29/343,307**

The ornamental design for a tube holder assembly with rounded distal end, as shown and described.

(22) Filed: **Sep. 10, 2009**

DESCRIPTION

(51) **LOC (9) Cl.** **24-01**

FIG. 1 is a generally top-directed perspective view of a tube holder assembly with rounded distal end in accordance with an embodiment of the present invention;

(52) **U.S. Cl.** **D24/224**

FIG. 2 is a generally bottom-directed perspective view of the tube holder assembly of FIG. 1;

(58) **Field of Classification Search** D24/216,

FIG. 3 is a top view of the tube holder assembly of FIG. 1;

D24/222-226, 227, 229, 230, 231, 232, 169;

FIG. 4 is a front view of the tube holder assembly of FIG. 1;

D10/81; D3/203.1-203.8; 422/99, 102;

FIG. 5 is a left side view of the tube holder assembly of FIG.

D9/503, 504, 505, 529, 530, 549; 435/288.1,

1; 435/288.3, 288.4, 304.1, 305.1, 305.3, 305.4

See application file for complete search history.

FIG. 6 is a right side view of the tube holder assembly of FIG. 1;

(56) **References Cited**

FIG. 7 is a bottom view of the tube holder assembly of FIG. 1; and,

U.S. PATENT DOCUMENTS

FIG. 8 is a rear view of the tube holder assembly of FIG. 1.
